UNITED STATES PATENT OFFICE.

GUY B. COLLIER, OF KINDERHOOK, NEW YORK.

INTERNAL-COMBUSTION MOTOR.

1,126,708.

Specification of Letters Patent.

Patented Feb. 2, 1915.

Application filed March 23, 1912. Serial No. 685,757.

To all whom it may concern:

Be it known that I, GUY B. COLLIER, a citizen of the United States, residing at Kinderhook, in the county of Columbia and State of New York, have invented certain new and useful Improvements in Internal-Combustion Motors; and I do hereby declare the following to be a full, clear, and exact description of the invention, such as will 10 enable others skilled in the art to which it appertains to make and use the same.

The present invention relates to internal combustion motors, and more particularly to rotary valve mechanisms employed in connection with this type of motor.

When this type of valve is subjected to the varying pressures occurring within the combustion chamber of the motor, an unbalanced pressure is exerted upon the valve, which 20 must be balanced automatically if the wear upon the valve is to be reduced to a minimum and a gas tight joint maintained between the valve and its seat.

The object of the present invention is to 25 provide a valve mechanism of this type which affords large port and passage areas for the admission and exhaust of the gases from the cylinder without leakage of the same, and which may be operated with a 30 small expenditure of power while maintaining a gas tight joint indefinitely.

With this object in view, the several features of the invention consist in certain novel features of construction, combinations 35 and arrangements of parts hereinafter described and claimed, the advantages of which will be obvious to those skilled in the art from the following description.

In the accompanying drawings illustrating the preferred form of the invention;

Figure 1 represents a front elevation of an internal combustion motor embodying the several features of the invention in their preferred forms; Fig. 2 is a section taken 45 upon the line 2—2 of Fig. 1, Fig. 3 is a section in elevation taken upon the line 3—3 of Fig. 2, looking in the direction of the arrows; and Fig. 4 is a sectional elevation of one cylinder of an internal combustion motor and a modified form of valve mechanism therefor.

In the illustrated embodiment of the invention, the motor is indicated at 1 and consists of the usual water jacketed cylinders, 55 indicated at 2, and each provided with pis-

tons 3 operatively connected to the crank shaft 4 through connecting rods 5. A single valve supplies two adjacent cylinders and the valve chamber is provided with a water jacketed valve seat housing 6 having a port 60 7 opening into each of the cylinders. A rotary valve is indicated at 8 and is provided with an inlet port 9 and an outlet port 10 which open into separate chambers formed in the interior of the valve and divided by 65 a partition 11. As will be noted from an inspection of Fig. 3, this valve is in the form of a hollow sleeve having open ends which communicate through the chambers with the inlet and exhaust ports of the valve. The 70 valve is rotated continuously to bring the inlet and outlet ports of the valve successively into register with the cylinder ports by a vertical shaft 13 which is driven from a valve shaft 15 through intermeshing bevel 75 gears 16 and 17. As will be noted from an inspection of Fig. 1, the cranks of the two adjacent cylinders are positioned 180° apart and the valve shaft 15 is driven at one half the speed of the crank shaft so that the inlet and exhaust ports of the valve, which are positioned 90° apart, are brought into 80 register with each cylinder port at the proper time. The above described construction forms no part of the present invention 85 and is fully described in the co-pending application of Wales, Serial No. 658,526, filed October 24, 1911.

This valve is employed in connection with a gas engine of the four-cycle type in which 90 the successive strokes of the piston are explosion, exhaust, suction and compression. During the exhaust and suction strokes of the piston, the exhaust and inlet ports of the valve respectively register with the cylinder port, but during the explosion and compression strokes of the piston the cylinder port is closed by the blank wall of the valve and the pressure of the gas in the cylinder upon this wall causes an unbalanced pressure to be exerted upon the valve if not compensated for in some manner.

In the present invention, a cylindrical valve is employed and is balanced laterally by applying to the valve diametrically opposite each cylinder port a pressure which is equal and oppositely directed to the pressure applied to the valve through the cylinder port.

It will be obvious that the only unbal-

anced pressure upon the valve which needs to be balanced automatically is the lateral pressure directed against the blank wall of the valve through each of the cylinder ports during the compression and explosion strokes respectively.

In the preferred form of the invention, the pressure tending to force the valve against its seat is slightly greater than the pressure through the cylinder port tending to force the valve away from its seat and varies in synchronism therewith, thus maintaining the valve in close contact with the seat adjacent the cylinder port and preventing any leakage of gas between the two surfaces. The valve 8 is cylindrical in form, as shown clearly in Fig. 3 of the drawings and rotates in a valve seat 20 which is secured in the valve seat housing 6. Each of the cylinders is provided with a pressure pipe 22 connecting the explosion chamber of the cylinder with two pressure chambers 24 and 25 formed in the top and bottom of the valve seat 20 diametrically opposite to the port 7 of the cylinder. The total lateral pressure exerted upon both the upper and lower portions of the valve by each pair of chambers is equal to or slightly greater than the pressure exerted through the opposite cylinder port, thus balancing the valve laterally without cramping in its seat.

Each chamber is provided with a dummy piston, indicated at 30, and having provision for a slight longitudinal movement in the chambers. The smaller end of the dummy piston is pressed against the wall of the valve to seal the chamber, preventing a leakage of gas out of the chamber between the valve and valve seat and contributing a part of the lateral balance. The inlet and exhaust ports are rectangular in form and extend only throughout a portion of the length of the valve, thus leaving a continuous band of metal around the upper and lower margins of the valve to seal the ends of the dummy piston. The outer portion of the chamber is enlarged and the dummy piston is provided with an annular flange which extends into the recess, the upper side of the flange forming an extended surface over which the pressure is applied to maintain the dummy piston in engagement with the valve.

In the construction shown, the chamber 55 is closed upon the outside by a threaded cap 31 which is tapped to receive a branch pipe leading from the main pipe 22. With this construction, the gas acting upon the outer extended face of the dummy piston 60 presses it firmly against the valve and prevents the passage of gas past the inner edge of the piston. As will be noted from an inspection of Fig. 3, the dummy piston is provided with a series of piston rings to cause it to fit closely in the chamber.

In order to reduce the friction between the valve and its seat to a minimum, and to allow the valve to rotate freely when expanded, the greater portion of the seat is cut away or recessed and a pair of oil leads 35 are connected with the upper part of the cut away portion to feed lubricating oil between the valve and seat. This oil is conveniently removed by providing an annular duct in the lower portion of the seat which communicates with a return pipe 36. With this construction, the valve is tightly held between the dummy pistons and the concentric portion of the valve seat adjacent to the cylinder ports and may be rotated with a minimum amount of friction.

The valve is efficiently cooled by providing a hollow shell, indicated at 37, which is connected at the top and bottom with passages formed in the spindle 38 of the valve. The valve is rigidly connected at its lower end to a shaft 40 which is provided with two passages registering with the passages in the spindle 38. This shaft passes through the bottom of the valve housing 90 and a gas tight joint, indicated at 41, prevents the escape of gas between the rotating shaft and the housing. The lower end of the shaft outside of the housing carries a stuffing box 45 which is provided with two chambers 46 and 47 communicating with the two passages in the shaft 40. A plurality of packing members, indicated at 48, surround the shaft 40 and serve to prevent leakage out of the stuffing box or from one chamber to another. With this construction, the open ends of the passages in the shaft 40 are always in communication with the chambers 46 and 47, thus enabling a continuous flow of water to be secured which passes through the shaft and water jacket of the valve.

The two chambers in the stuffing box are connected with any convenient type of water circulating system through flexible connections, indicated at 50 and 51 respectively. The stuffing box is held against rotation by an L-shaped bracket 53 secured to the wall of one of the adjacent cylinders and having a bifurcated outer end which engages opposite sides of a stud 54 projecting laterally from the stuffing box. This construction prevents any rotation of the stuffing box, but allows a free lateral and vertical movement of the stuffing box.

In order to compensate for any eccentricity between the shaft 13 and the shaft 40, a universal joint connection, indicated at 55, is provided for connecting the two shafts together. The valve is prevented from moving vertically when the motor is subjected to shocks and jars by an annular ring 60 interposed between the upper face of the valve and the top of the valve casting, and adjusted by a plurality of ad-

justing screws 61 threaded in the upper portion of the valve housing and bearing against the upper face of the ring.

The construction shown in Fig. 4 illustrates a modified form of mechanism for balancing the lateral pressure exerted upon the valve through the cylinder port. In this construction, the cylindrical valve is indicated at 65 and is balanced laterally by a pair of pressure chambers 66 and 67 which are positioned diametrically opposite to the cylinder port 68. These chambers are connected with the combustion chamber of the cylinder through a pipe, indicated at 69, and each chamber is provided with a dummy piston 70 of the usual form to seal the chamber and prevent leakage of the gas between the wall of the valve and the valve and housing. In order to maintain a tight joint between the valve and seat adjacent the cylinder port, a dummy piston 71 is slidably supported in the cylinder port and is arranged with its inner edge bearing against the wall of the valve. The outer face of this piston is subjected to the varying pressures within the combustion chamber and serves to maintain a tight joint between the valve and seat at this point.

In the construction shown in the drawings, the dummy piston is slidably supported in a sleeve 78 threaded in the wall of the cylinder and enabling the dummy piston to be readily inserted and removed from the valve when desired. In this construction the inlet and exhaust ports of the valve are circular in form and register accurately with the bore of the piston.

The valve is retained from vertical movement in its seat by an annular ring 72 interposed between the upper face of the valve and the top of the valve housing. Cooling water is led into an internal water jacket formed in the wall of the valve through a passage 73 formed in the spindle and communicating at its upper end with the water jacket. The lower end of the passage opens into a chamber 74 formed in a stuffing box 75 which is secured to the under side of the valve housing. The stuffing box 75 is provided with the usual packing member 76 and a water intake pipe 77. The upper end of the valve spindle extends above the valve housing and is provided with a water passage 80 which communicates with the upper portion of the water jacket and serves to lead the heated water away from the valve. This passage opens

into a chamber 81 formed in a stuffing box 82 which is secured to the upper portion of 60 the valve housing. The stuffing box is provided with the usual packing members 83 and a return pipe 84 to remove the heated water from the valve.

While it is preferred to employ the specific construction and arrangement of parts shown and described, it will be understood that this construction and arrangement is not essential except so far as specified in the claims, and may be changed or modified without departing from the broader features of the invention.

The invention having been described, what is claimed is:

1. An internal combustion motor, having 75 in combination, a power cylinder, a valve chamber having a port opening into the cylinder, a cylindrical valve having a port midway of its ends arranged to register with the cylinder port, means for continuously 80 rotating the valve, a plurality of pressure chambers located diametrically opposite the cylinder port adjacent the ends of the valve and disposed symmetrically in a longitudinal relation to the valve in order to 85 equalize the balancing pressure exerted upon the ends of the valve, and connections between the pressure chambers and the cylinders.

2. An internal combustion motor comprising 90 a cylinder, a valve housing supported adjacent to the cylinder, a water jacketed valve rotating therein, a valve spindle having passages formed therein and connecting with the water jacket of the valve, a stuffing box surrounding the lower end of the spindle and inclosing the open ends of the passages, and connections for leading cooling water to and from the stuffing box, substantially as described.

3. An internal combustion motor comprising 100 a cylinder, a valve housing supported adjacent to the cylinder, a hollow sleeve valve rotating therein and provided with double walls to form a water jacket, a valve 105 spindle for rotating the valve having a plurality of passages formed therein connecting with the water jacket of the valve, and water tight connections for leading water to and from the passages, substantially as described.
